UNITED STATES PATENT OFFICE.

THOMAS W. MORGAN, OF WATERLOO, IOWA, ASSIGNOR TO WILBUR W. MARSH, OF WATERLOO, IOWA.

MAGNETO-GENERATOR.

1,153,944.

Specification of Letters Patent. Patented Sept. 21, 1915.

Original application filed March 26, 1912, Serial No. 686,205. Divided and this application filed October 27, 1913. Serial No. 797,378.

To all whom it may concern:

Be it known that I, THOMAS W. MORGAN, a citizen of the United States, and a resident of Waterloo, in the county of Blackhawk 5 and State of Iowa, have invented certain new and useful Improvements in Magneto-Generators, of which the following is a full, clear, and exact specification.

My invention relates to magneto generators, and has more particular reference to improvements in magnetos of the class used in ignition systems for internal combustion engines.

One of the objects of my invention is to 15 provide an improved magneto which will be simple, durable and reliable in construction, and effective and efficient in operation.

Another object of my invention is to provide an improved magneto structure which 20 will be so constructed and arranged that the parts thereof will be interchangeable and may be manufactured in large quantities and assembled without adjustment.

A further object of my invention is to 25 provide an improved field pole-piece, which may be formed up from sheet metal without the aid of expensive machine work.

Another object of my invention is to provide a magneto having improved means for 30 conveniently timing the magneto with the engine with which it is used, without disturbing the parts of the magneto or necessitating its being disassembled.

This application is a division of my co- 35 pending application Serial No. 686,205, filed March 26, 1912.

To the attainment of these ends and the accomplishment of other new and useful objects, hereinafter appearing, my invention, 40 consists in the features of novelty disclosed in the construction, combination, and arrangement of parts and hereinafter described and claimed, and shown in the accompanying drawings, which illustrate one embodiment of my invention, and in which—

Figure 1 is a central longitudinal vertical section of a magneto generator embodying 50 my invention. Fig. 2 is a transverse vertical section on the line 2—2 of Fig. 1. Fig. 3 is a transverse vertical section on the line 3—3 of Fig. 1, the end of the armature being shown in elevation. Fig. 4 is a horizontal section partly in elevation on the line 4—4

of Fig. 3, and, Fig. 5 is a detail perspective view of a device for holding the clamping bolts from turning.

In the drawings I have illustrated my invention as embodied in a magneto generator designed to be used more particularly for igniting the charge in gas engines of the single cylinder type adapted for rotation in either direction, but it will be clearly manifest to one skilled in the art, after having obtained an understanding of my invention from the disclosures herein made, that my invention is not restricted to the particular structure shown, nor is its application limited to single cylinder engines.

The magneto shown in the drawings has a 70 casing or frame A, which is preferably constructed as an inclosure so as to protect the operating parts of the magneto from dirt and injury. Access, however, must be gained to the interior thereof at times for 75 the purpose of inspection, cleaning and repair, hence it is necessary to occasionally disassemble the structure. It is desirable, therefore, that the structure be capable of being assembled in operative relation with- 80 out further adjustment than the mere placing together of the parts.

In the structure shown the frame A has journal bearings 1 and 2 at the ends thereof, preferably formed integral therewith. 85 The frame is preferably divided into two sections separably fitted together at their abutting edges 3 and 4 respectively, as shown in Figs. 1 and 2. These abutting edges are formed as lap or shoulder joints 90 and are curved on arcs, the center of which is the axis of the journal bearings, hence when the two frame sections are placed together the bearings will always properly line up without further adjustment. The 95 sides 5 of the frame are faced off so that they lie in planes parallel to each other. The base portion 6 of the frame projects laterally as shown, so as to form ledges 7, upon which the ends of the permanent field magnets 8 rest; hence the magnets 8 will always be positioned properly in relation to the frame without the necessity of further adjustment each time the parts are assembled.

Each side of the frame is provided with 105 a detachable field pole-piece which projects into the open side thereof and embraces the rotary armature D. In the structure shown

in Figs. 1 to 4, inclusive, the pole-pieces are composed of arc-shaped plates 9 and flat supporting plates 10, but as shown in Figs. 6 to 9 inclusive, and 12 and 13, they may be formed up from one piece of metal. The pole-piece plates 9 are preferably rectangular and are blanked out and formed or pressed up from sheet metal of suitable thickness. The pole-piece plates 9 after being given an arc-shaped formation are faced off flat as indicated at 12, (Figs. 2 and 3), so that they may be firmly mounted on the backing or supporting plates 10. The two plates comprising each pole-piece 15 may be securely fastened together by means of several rivets 13, the heads of which preferably do not project beyond the plate surfaces. The supporting plates are rectangular but somewhat longer than the field 20 plates, and are provided with holes 10⁴ at their corners through which bolts 14 may be inserted and screwed into the frame section (Fig. 4) to clamp the pole-pieces in position at the sides of the frame and at 25 the same time hold the frame sections together. As is manifest, the pole-pieces also serve to completely close the open sides of the frame and prevent moisture and dirt from gaining access to the interior mechanism. The permanent field magnets 8 bridge the frame structure, and their lower ends 8¹ as before mentioned rest on the ledges 7 of the base 6. These magnets may be firmly crimped flatly against the plates 30 10 by means of the plates or strips 15, the bolts 16 and nuts 17. The clamping bolts 16 may be inserted through suitable holes in the backing plates 10 from the inner sides thereof, and may be long enough to project 35 beyond the magnets and receive the clamping plates or strips 15 and nuts 17. These bolts may be prevented from turning by means of small metal clips 18 (Fig. 5). The clips 18 as shown are placed between 40 pole-piece plates 9 and 10 and one of their edges 19 are arranged to fit the slots in the heads 20 of the bolts. The edges 19 have 45 loops 21 to prevent the clips from becoming displaced endwise.

50 The armature D is preferably of the bipolar type comprising the two heads or poles 25 connected by a core 26, and a suitable winding 27 on the core between the poles. The ends of the armature may be 55 provided with disks or circular plates 29 and 30, which may be secured thereto, so as to be easily disassembled, by means of a number of screws 31. These end plates or disks 29 and 30 carry the centrally positioned stud shafts 32 and 33, arranged in axial alignment and rotatably mounted in the journal bearings 1 and 2 respectively. The shaft 33 is hollow and carries an insulating sleeve 34, having a metal plug 35 inserted in its inner end. On this plug is a

terminal clip 36, to which one end of the armature winding may be connected. A brush 37 is mounted in the outer end of the insulating sleeve 34 and operates in the hollow end of a binding post or terminal 70 38, and this brush is yieldingly seated in position during the rotation of the armature by means of a spring 39 interposed between the inner end of the brush and plug. The binding post 38 is mounted in an insulating plug or cap 40 set into the end of the journal bearing 2 and is fastened in place by a set-screw 41, whereby it may be readily removed and access gained to the interior of the bearing whenever desired. 75 The other terminal (not shown) of the armature winding may be grounded directly on the armature metal as usual. The other shaft 32 projects beyond the end of the bearing 1 a sufficient distance to receive 80 a gear for driving the magneto. 85

Magneto generators of the character herein described are more particularly used in connection with the ignition of gas engines, and, as is well known, it is customary to mount the magneto on the frame of the engine in such position that a train of gears or a chain belt may be connected between the armature shaft 32 and the engine shaft for the purpose of driving the magneto, and these driving mechanisms are proportioned to drive the magneto at a speed consistent with the speed of the engine, to secure the best sparking results. It is also customary to connect the insulated terminal 38 of the magneto with the corresponding insulated terminal of the make-and-break sparking apparatus of the gas engine, and to ground the other terminal of the armature winding on the frame of the machine. 100 105

My improved magneto is designed more particularly for use in connection with gas engines intended to run in either direction, and since the magneto is connected therewith by a positive driving mechanism, as above mentioned, the magneto must necessarily run in either direction corresponding to the engine. It is a matter of common knowledge in magneto generators of the bipolar type, that the alternating current wave reaches its maximum value when the polarity of the armature is reversed at a certain point in its revolution, hence the current is of maximum value for sparking or ignition purposes at this point. This point, however, as is well known, changes in accordance with the direction of rotation of the armature. For instance, in the structure shown, during the rotation of the armature in the direction of the arrow (Fig. 3) the current rises to its maximum value when the armature poles 25 reach substantially the position indicated by the dotted line X—X. During the opposite direction of rotation the current rises to max- 110 115 120 125 130

imum value at about the time the armature arrives in the position indicated by the dotted line Y—Y. In order, therefore, to secure the best sparking results, the magneto 5 should be timed so that the spark takes place when the armature is in either of these positions, depending on the direction of rotation. This is usually done by adjusting the gear on the armature shaft until 10 the position of the armature is timed or coincides with the make-and-break apparatus of the engine. Hence, whenever the direction of rotation of the engine is reversed, it is necessary to change the adjustment of 15 the magneto with respect thereto. In the present magnetos on the market the magneto must be partially disassembled so that the armature can be seen while the adjustment is being made. To avoid all of these 20 objections, I predetermine the positions of the armature and provide timing mechanism accessible from the outside of the magneto frame whereby the armature may be temporarily held in either of its predetermined 25 positions without disturbing or disassembling the parts in any manner. This mechanism is arranged to automatically release the instant the armature is rotated after adjustment. Referring more particularly 30 to Figs. 3 and 4, it will be observed that in the end of the frame section which carries the journal bearing 1, there is provided two small headed pins or plugs 45, one on each side of the shaft 32, and preferably arranged in a horizontal plane. These are freely movable longitudinally in 35 the frame. They project outwardly beyond the casing in such manner that they may be readily pressed inwardly by the fingers. 40 The end plate or disk 29 of the armature may be provided with a small depression or socket 47, so disposed that when the socket is alined with one or the other of the stop pins 45, the armature will be in 45 one or the other of its predetermined positions, indicated by the dotted lines X—X or Y—Y, depending upon the direction of rotation of the armature. The head 46 of a stop pin, when the pin is pressed inwardly, 50 enters the timing socket 47 and thereby the armature may be held against rotation as long as the pressure is maintained on the pin, but as soon as the pin is released the rotation of the armature automatically 55 throws the pin outwardly in a non-holding position. It will thus be seen that when it is desired to time the magneto with the engine it is simply necessary to loosen the gear on the armature shaft, press inwardly 60 the pin corresponding to the desired direc-

tion of rotation of the armature, and turn the armature until the pin engages the depression 47. Thus the armature may be held in its predetermined position while the 65 sparking apparatus is timed therewith. The gear on the armature shaft may then be tightened.

It will be observed that my invention is capable of various modifications without departing from the spirit thereof, and I wish 70 it to be clearly understood that I am not limited to the particular structure shown in the drawings.

What I claim as new is:

1. In a magneto generator, the combination of a frame, an armature journaled in said frame and inclosed by the latter, said armature being provided with a recess therein, and two pins slidably mounted in said frame, one of said pins when the armature is rotated in one direction being adapted to engage the recess when a maximum current is generated in the armature, and the other of said pins being adapted when the armature is rotated in the other direction 80 to engage the recess when a maximum current is generated in the armature.
2. In a magneto generator, the combination of a frame, an armature journaled in said frame and inclosed by the latter, said armature being provided with a recess substantially conical, and a pin slidably mounted in said frame and having a rounded head thereon adapted to be brought into engagement with said recess, the shape of the head 90 and recess causing the head to ride out of the recess upon rotation of the armature.
3. In a magneto generator of the class described, the combination of a frame, an armature rotatable in and inclosed by said 100 frame, field magnets mounted on the frame in relation to said armature, a freely movable pin mounted in the end of said frame on each side of the axis of rotation of the armature and corresponding to the position 105 wherein the maximum current is developed in said armature depending upon the direction of rotation thereof, and a depression in the end of said armature adapted to be engaged by either of said pins depending 110 upon which one is actuated.

In testimony whereof I have signed my name to this specification, in the presence of two subscribing witnesses, on this 22nd day of October A. D. 1913.

THOMAS W. MORGAN.
